DOUBLE RATCHET WRENCH

Edmund C. Trautman, Seattle, Wash.

Application August 19, 1940, Serial No. 353,287

2 Claims. (Cl. 81—57)

My invention relates to new and useful improvements in wrenches.

An important object of my invention is to provide a wrench that has provision for rapidly rotating a spindle on which a socket is adapted to be detachably mounted whereby relatively loose nuts, screws, or bolts may be tightened.

Another object of my invention is to provide a wrench that includes means for tightening a nut after the same has been threaded onto the bolt, which wrench requires no adjustment to render the tightening means operative after the first means has been used to initially thread the nut or bolt into the tightening position.

Still another object of my invention is to provide a wrench of the above-mentioned character that operates with equal efficacy for unthreading the nut or bolt which unthreading operation requires no adjusting or interchanging of the parts of the wrench.

Other objects and advantages of my invention, will be apparent during the course of the following description.

In the drawing, forming a part of this specification, and wherein like numerals are employed to designate like parts throughout the same,

Figure 1 is a longitudinal sectional view of a wrench embodying my invention taken on the line 1—1 of Figure 2,

Figure 2 is a longitudinal sectional view taken on the line 2—2 of Figure 1,

Figure 3 is a fragmentary transverse sectional view taken on the line 3—3 of Figure 2, and

Figure 4 is a fragmentary transverse sectional view taken on the line 4—4 of Figure 2.

In the accompanying drawing, wherein for the purpose of illustration, is shown a preferred embodiment of my invention, the numeral 10 designates a body for receiving the operating parts of the wrench, which body comprises an elongated handle portion 11 provided at one end with an enlarged integral head portion 12. In side elevation, the side walls 12' and 13' of the head diverge outwardly from the handle, which outwardly diverging sides are connected by an integral arcuate end wall 13. In plan, the substantially knob-like head thus formed is provided with flat rear and front surfaces 14 and 15, which face 15 tapers outwardly from the body, as at 16, to provide an essentially thick front wall 17. The front wall 15, side walls 12' and 13' and end wall 13 of the body are preferably formed integrally while the rear wall 14 is in the nature of a panel fixedly secured within the side and end walls and flush with the edges thereof.

5 The handle of the body is provided adjacent the side 14 thereof with a passage, which passage is longitudinally divided by a partition member 23 one end of the partition extends flush with the distal end of the handle and the other end thereof is enlarged and extends a substantial distance into the head. One end of the vertically spaced parallel passages or guides 18 and 19 are formed by the partition opens through the distal end 20 of the handle and the other end thereof registers tangentially with an essentially circular opening 21 defined by the end wall 13 and the last-mentioned end of the partition 23.

15 A spindle 22 extends through the head at substantially the radius at the curved end 13 and the essentially thick front wall 17 of the head is formed with a recess 24 which centrally receives the spindle. The opening 21 accommodates a sprocket gear 25 which is loosely mounted for 20 independent rotation about the spindle. The end of the partition confronting the sprocket is provided with a medial arcuate recess 26 which opens into the opening 21 and embraces the teeth of the sprocket gear.

25 The portion of the spindle extending through the sprocket is provided with a plurality of circumferentially spaced ratchet teeth 27 which are milled or otherwise cut into the periphery of the spindle. The sprocket is formed with a recess 28 which extends from and opens into the central spindle receiving bore and the spring pressed dog 29 is pivotally mounted therein to engage with the ratchet teeth 27. Engagement of the dog with the ratchet teeth holds the 30 sprocket fixedly connected to the spindle when the handle is rotated about the spindle in the direction of the arrow in Figure 4. Conversely, if the handle is rotated about the spindle in a direction opposed to the direction indicated by 35 the arrow, the dog 29 will ratchet over the teeth 27 so that the spindle will not be rotated.

30 The chain 30 extends around the sprocket and has its ends received within the passages 18 and 19. The end 31 thereof disposed within the upper 45 passage 18 is pivotally connected to one end of a rod 32, the other end of the rod being connected to the closed end 33 of a sleeve 34. The sleeve slidably receives the handle of the body and, when the sleeve is reciprocated relative to the 50 body handle, the chain is caused to travel back and forth in the passages.

Thus, when the handle is in the full line position illustrated in Figure 1, the free end 35 of the chain will extend substantially all the way into the lower passage 19 and the guide 36 piv-

totally secured thereto will be disposed in abutting relation with the end 37 of the passage. If, however, the sleeve is moved to the dotted line position of Figure 1, the rod 32 will be substantially entirely retracted from the passage 18 and the end 31 of the chain will be moved to substantially the outer end of the passage. The lower end thereof will thus be caused to move substantially forwardly within the lower passage and by reason of the interengagement of the chain and sprocket, the sprocket will be caused to rotate. When the sleeve is being pulled outwardly from the handle to rotate the sprocket, the dog 29 will engage one of the ratchet teeth 27 whereby rotation of the sprocket will effect the rotation of the spindle. When the sleeve is pushed onto the handle, the reversely moving chain will also effect rotation of the sprocket; however, the return rotation will not be transmitted to the spindle for the reason that the dog will move easily over the ratchet teeth 27.

The recess 24 receives the gear 38 which is fast on the spindle. The dog 39 is pivoted to the body by the bolt 44 in a manner whereby the free end thereof will be normally held in engagement with the teeth of the gear by the coil spring 40. The dog inclines downwardly from its pivot to engage the teeth of the gear in a manner whereby it will ratchet freely over the teeth when the handle is rotated about the spindle in a direction opposed to the direction of the arrow in Figure 4. If, however, the handle is rotated in the direction of the arrow, the dog will engage the teeth of the gear to connect the spindle to the body and to effect direct rotation therebetween. The ends 41 and 42 of the spindle extending from the opposite sides of the head are substantially square and certain of the faces are provided with spring pressed detents 43 adapted to detachably secure a socket thereon.

The socket or screw driver attachment is applied to the end of the spindle and fitted onto the bolt or screw which is to be loosely threaded on a nut or into an object and the sleeve 34 is rapidly reciprocated. At each outstroke of the sleeve the chain will effect rotation of the sprocket 25 and the dog 29 will connect the sprocket with the spindle whereby the socket or screw driver attachment will be rapidly rotated. The rotation of the spindle during the outstroke of the sleeve will cause the dog 39 to ratchet freely over the teeth of the gear 38. During the instroke of the sleeve the sprocket gear will again be rotated, however, the dog 29 will freely move over the ratchet teeth 27 whereby rotation of the socket or screw driver attachment at the end of the spindle will not be effected.

Reciprocation of the sleeve will thus permit the nut or screw to be rapidly rotated onto the bolt or into the mentioned object. As soon as

the nut or screw begins to bind and reciprocation of the sleeve becomes difficult, the body itself may be rotated about the spindle. The extending handle and sleeve offer substantial leverage and movement of the wrench in a direction to further tighten the bolt will cause the dog 39 to engage between adjacent teeth of the gear 38. Thus, further rotation of the body above the spindle will connect the body to the spindle and effect rotation of the socket.

It is not necessary that any parts be changed or adjusted when the wrench is converted from a rapid operating to a slow operating wrench. For rapid operation the body is held stationary and the sleeve is reciprocated, and for slow heavy duty the body and sleeve together are moved angularly about the spindle. This simplicity of construction and operation is highly desirable in that there are comparatively few working parts to become broken or damaged. The wrench may be inexpensively manufactured and it is characterized by substantial practical utility when used under conditions where speed and dependability are of paramount importance.

It is to be understood, that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. In a wrench, a body having guideways, a spindle mounted for rotation within the body at one end of the guideways, a sprocket loosely mounted on the spindle, a ratchet coupling the sprocket to the spindle, a chain connecting with the sprocket and having its ends received within the said guideways, reciprocative means carried by the body and connecting with one end of the chain, a gear fixed to the shaft, and a pawl coupling the gear to the body, both said ratchet and said pawl overriding their respective gears when the spindle is rotated in one direction.

2. In a wrench, an elongated body, a spindle formed with a plurality of circumferentially spaced ratchet teeth for a portion of its length mounted for rotation at one end of said body, a reciprocative sleeve mounted at the other end of the said body, a gear loosely mounted on the spindle to cover the ratchet teeth, said gear having an inner recess opening against the ratchet teeth, a chain extending over the loose gear and connecting at one end with the said sleeve, a ratchet mounted within the gear recess for coupling the said gear and spindle, when the gear is rotated in one direction, a second gear fixedly mounted on the spindle, and a pawl coupling the last gear and body.

EDMUND C. TRAUTMAN.
